US0D1047684S

(12) **United States Design Patent** (10) **Patent No.:** **US D1,047,684 S**
(45) **Date of Patent:** **** Oct. 22, 2024**

(54) **PACKAGING**

- (71) Applicant: **SIG Services AG**, Neuhausen am Rheinfall (CH)
- (72) Inventors: **Norman Gierow**, Duesseldorf (DE); **Matthias Krusche**, Aachen (DE)
- (73) Assignee: **SIG Services AG**, Neuhausen am Rheinfall (CH)
- (**) Term: **15 Years**
- (21) Appl. No.: **29/833,190**
- (22) Filed: **Apr. 1, 2022**

Related U.S. Application Data

- (62) Division of application No. 29/693,179, filed on May 31, 2019, now Pat. No. Des. 950,377.
